[57] CLAIM

The ornamental design for a car interior light, as shown and described.

DESCRIPTION

FIG. 1 is an exploded perspective view of a car interior light showing my new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a rear view thereof.

The electric cord is broken away in FIG. 1 and fragmentarily shown in FIGS. 2-5 and FIG. 7 for convenience of illustration.
